Improvements in
Nursing or Easy Chair, patent 1 Jan 26, 1899.

When the foot rest a is not in use it is turned down upon the foot board b with the strap c folded between them.

Fig 2 shows a right angled working board c, pivoted at d, & carrying a roller e. Operated by pulling on upper end or passing a cord from the ring f, over a pulley on the chair & back to the occupant's writing table K consists of arms R hinged at m so as to swing over the back, & carrying a cross bar L. Prop a support table at an inclination. Table g is hinged to cross bar L so as to pass over top back when folded out of the way.

Wing g is pivoted to arm so fall down when the prop g is released, & attached to a pentrough h or pivotally mounted so that the centers of gravity will cause them to maintain vertical position when wing g is open or folded.

Wing g holds back from falling down.
